HARVEY J. RUSSELL, OF NORTH BEND, OREGON.

AUTOMATIC CONTROL MEANS FOR AIR-PRESSURE PUMPS.

1,229,792.

Specification of Letters Patent. Patented June 12, 1917.

Continuation of application Serial No. 793,759, filed October 6, 1913. This application filed November 27, 1915. Serial No. 63,874.

To all whom it may concern:

Be it known that I, HARVEY J. RUSSELL, a citizen of the United States, residing at North Bend, in the county of Coos and 5 State of Oregon, have invented a new and useful Automatic Control Means for Air-Pressure Pumps, of which the following is a specification.

This invention has reference to automatic 10 control means for air pressure pumps and is designed to provide an automatic release that will effectively prevent over-pressure.

This invention contemplates the use of a cylinder to be attached to the pump cylinder and containing a piston constrained toward one end of the cylinder by a spring, the piston yielding to a pressure established on that side of the piston remote from the spring by a connection to the discharge side 20 of the pump. A relief valve in the pump is under the control of a rockable member normally latched in the inactive position and released therefrom by a movement of the piston in the controlling cylinder when 25 the air pressure shall have reached a certain predetermined maximum. The rock member not only causes the opening of the relief valve under such conditions, but is held in such position by another latch until 30 the pressure shall have been relieved to an extent permitting the piston of the control device to move back to its first position, whereupon the rock member is released from its second latched position to return to the 35 first position where it is again latched as at the beginning.

Instead of having the air under pressure acting directly on the piston in the control cylinder, a flexible diaphragm is provided 40 thus doing away with any necessity of packing the control piston, for not only is leakage avoided, but the friction which in the device of the aforesaid application was necessarily present in the piston packing, is entirely avoided by the elimination of such packing.

The invention will be best understood from a consideration of the following detailed description, taken in connection with 45 the accompanying drawings forming a part

of this specification, with the further understanding that while the drawings show a practical form of the invention, the latter is not confined to any strict conformity with the showing of the drawings, but may be 55 changed and modified so long as such changes and modifications mark no material departure from the salient features of the invention.

In the drawings:

Figure 1 is an elevation with some parts broken away and in section showing the automatic control means of the present invention applied to an air pump.

Fig. 2 is a longitudinal central section 65 through the control cylinder with parts carried thereby in elevation.

Fig. 3 is an elevation of the structure of Fig. 2 as seen from the right hand end of 70 said figure.

Fig. 4 is a plan view of the structure of Fig. 2.

Fig. 5 is a section on the line 5—5 of Fig. 2.

Fig. 6 is a perspective view of one of 75 the latches.

Referring to the drawings there is shown an air pump cylinder 1 and a portion of a piston rod 2, as well as an outlet pipe 3 leading from the discharge end of the pump to 80 a point of disposal of the compressed air. In the showing of the pump no attempt is made to disclose any particular structure, since the present invention is not confined in its use to any particular structure of air 85 pump, but may be applied to various types thereof. For this reason the showing of the air pump is to be taken as merely indicative of any type of air pump. At the discharge end of the pump there is installed 90 a relief valve 4 having a valve stem 5 movable through a gland 6. The stem 5 terminates at the outer end in a head 7 between which and the gland the stem is surrounded by a spring 8 tending at all times to maintain the valve 4 in the closed position, which position is further maintained by air pressure within the pump 1.

It will be understood that the present invention may have a wider application than 100

in connection with air pumps, but for convenience of description the pump 1 will be considered an air pump and will be so termed throughout the following specification without a limitation of the invention strictly thereto.

Attached to the cylinder of the pump 1, as by a bracket 9, is another cylinder 10 which may be of relatively small size as compared to the cylinder of the pump 1, and the bracket 9 may be secured to the cylinder 10 by screws 11 or otherwise, being in turn connected to the cylinder of the pump 1 by screws 12 or in any suitable manner.

As shown the cylinder 10 is of even diameter throughout with one end internally screw-threaded, as indicated at 13 and the other end externally screw-threaded, as indicated at 14, and in the usual installed position of the device the end with the threads

13 may be considered as the upper end and the end with the threads 14 may be considered as the lower end. Applied to the screw threads 14 is a cylinder head 15 having a central boss 16 and an axial passage 17 extending through the boss 16. The inner face of the head 15 may be somewhat dished, as indicated at 18, and confined between the head and the corresponding end of the cylinder 10 is a disk or diaphragm 19 of flexible material, such as leather, or some material of like function for the purposes of the invention. Entering the passage 17 is one end of a pipe 20, the other end of which is connected to the outlet pipe 3 of the pump 1. The pipe 20 is in free communication with the passage 17 and the pipe 3, and, therefore, in the space between the diaphragm 19 and the face 18 of the head 15 there is always established an air pressure corresponding to the pressure within the pipe 3.

Located within the cylinder 10 is a piston 21 which may fit the interior of the cylinder 45 with a certain freedom, whereby the piston is not subjected to any particularly frictional resistance in its movements in the cylinder 10. This piston has a slightly convex face 22 presented toward the diaphragm 19. Connected at one end to the piston 21 is a piston rod 23 extending lengthwise of the cylinder and through a cylinder head 24 exteriorly threaded and applied to the threaded end 13 of the cylinder 10. Bearing 55 at one end against the piston 21 and at the other end against the head 24 is a coiled spring 25 tending at all times to maintain the piston 21 against the diaphragm 19. When the spring 25 is lodged within the cylinder 10 and the head 24 is applied, such head is screwed along the threads 13 until the spring is under a predetermined compression, which compression may be varied by screwing the head 24 in the appropriate

direction in the cylinder 10, wherefore the amount of air pressure needed to compress the spring in opposition to its normal expansive tendency may be varied at will. When air pressure is established on the side of the diaphragm 19 toward the head 15, and this air pressure increases sufficiently the piston 21 is moved in a direction to further compress the spring 25, and when the air pressure is reduced sufficiently the expansive force of the spring 25 overcomes the air pressure so that the piston 21 is restored to its first position. The diaphragm 19 being made of flexible material readily yields to the variations of air pressure, and yields sufficient for the purposes of the present invention. The head 24 is provided with a hub 26 exteriorly shaped for the application of a tool to facilitate the adjustment of the head.

Rising from the bracket 9, and preferably though not necessarily in one piece therewith, is a post 27 extending for an appropriate distance above the cylinder 10, and this post may be bifurcated at its upper end and there carries a rock lever 28 having an arm 29 extending over the cylinder 10 diametrically thereof, and another arm 30 extending over the pump cylinder so that its free end overrides the head 7 of the stem 5 of the relief valve. Extending laterally from the post 27 in a direction away from the cylinder 10 is an arm 31 having an angle extension 32 rising from the end of the arm remote from the post 27 and in substantial parallelism with the post 27. The extension 32 extends to a less height than the post 27 and at its upper end carries, by means of a pivot pin or screw 33, a latch lever 34 having at one end a nose 35 and at the other end provided with a pin 36 to which is attached one end of a coiled spring 37, which in turn has its other end secured to a pin 38 on the arm 31. The arrangement is such that the arm 30 of the lever 28 may strike the nose 35 on movement toward the pin 33 or extension 32, and this nose being appropriately rounded is forced out of the way of the arm 30, the spring 37 then yielding. As soon as the arm 30 has moved beyond the nose 35 in its travel toward the extension 33, the reaction of the spring 37 causes the nose to snap over the arm, thus locking or latching it against return movement.

Fast to the cylinder 10 at a point diametrically opposite from the post 27 is another post 39 which may be secured to the cylinder by screws 40 or otherwise, and this post rises to about the height of the extension 32 of the arm 31, although such particular proportions are not obligatory.

Carried by the post 39 near its upper end is a latch lever 41 pivoted to the post by

a screw or pin 42. One end of the latch lever 41, which is shown separately in Fig. 6, is provided with a nose 43, while the other end of the latch lever carries a pin 44 to which is secured one end of a coiled spring 45, and the other end of this coiled spring is connected by a pin 46 to the post 39. The latch levers 34 and 41 may be practically identical in form, and the latch or 10 latch lever 41 is designed to engage the free end of the arm 29 of the lever 28 when moved sufficiently toward the upper end of the post 39.

Carried by the post 27 below the lever 28 15 is another lever 47 pivoted to the post 27 by a pivot screw 48 or in any other appropriate manner. The lever 47 has an arm 49 which may terminate in a tapered extremity 50 moving alongside of the post 39, so as to engage the latch lever 41 to rock the lever against the action of the spring 45 for a purpose to be described. The lever 47 has another arm 51 lodged alongside of the extension 32 in position to engage the latch 20 lever 34 to move it against the action of the spring 37 for a purpose to be described. The arm 49 of the lever 47 is connected by a screw or pin 52 or otherwise to the piston rod 23, which rises a sufficient distance above 25 the head 24, and this pivot connection provided by the screw 52 may be sufficiently loose to permit the lever 47 to be rocked for an appropriate distance by a longitudinal movement of the piston rod. The end 50 of 30 the arm 49 is connected to a corresponding portion of the arm 27 by a coiled spring 53, and the outer end of the arm 51 is connected to a corresponding portion of the arm 30 by a coiled spring 54.

40 The normal position of the parts when there is no air pressure within the air pump, or such air pressure is less than the predetermined maximum, is that shown in Fig. 2, except that the piston 21 may be considered 45 as just beginning to rise under the air pressure, since in the absence of any material air pressure the piston forces the diaphragm 19 close against the face 18 of the head 15.

As the air pressure increases the diaphragm 19 is lifted, and with it travels the head 21 compressing the spring 25. This movement continues until the end 50 of the arm 49 has by engagement with the latch 41 rocked it on its pivot 42 and the nose 43 has 50 been swung to one side out of the path of the arm 29 of the lever 28. In the meantime the arm 51 of the lever 47 has been moving away from the arm 30 of the lever 28 then held against movement by the latch 41 and the 60 spring 54 has been correspondingly extended and put under superior tension. Now, as soon as the latch nose 43 has released the lever 28, the reaction of the spring 54 is sufficient to move the valve 4 away from its seat,

thus opening the interior of the pressure 65 side of the pump 1 to the atmosphere, and the pump 1 instead of increasing the pressure within the pipe 3 discharges into the atmosphere. The rocking of the lever 28 due to the spring 54 has caused a movement of 70 the lever 28 from its first position shown in full lines in Fig. 2 to the dotted line position shown in Fig. 2. This movement is sufficient to bring the arm 30 of the lever 28 below the nose end 35 of the latch 34, which 75 in the meantime has been released by the movement of the arm 51 in a direction away from the pivot 33, so that when the arm 30 has moved past the nose 35 the latter snaps over the arm 30, thereby locking it against 80 return movement so long as the latch 34 is held in the locking position by the spring 37 and is not acted upon by the arm 51.

The lever 28 when in the locked position last described positively holds the valve 4 85 open, and this without regard to the condition of pressure within the cylinder 10 so long as such pressure is sufficient to hold the arm 51 out of actuating engagement with the latch 34.

As soon as sufficient air has escaped through the opening unclosed by the valve 4 under the conditions last described, the pressure within the pipe 20 drops to a degree permitting the spring 25 to return the piston 21 to its first position. This results in the release of the latch 41 by the terminal portion 50 of the arm 49 and the movement of the arm 51 into engagement with the latch 34 actuating the latter against the tendency 95 of the spring 37 until the nose 35 releases the lever 28. In the meantime the return rocking movement of the lever 47 has released the tension upon the spring 54 and increased the tension upon the spring 53, so 100 that now the lever 28 is strongly urged away from the head 7 and toward the latch 41 to which position it quickly moves and the nose 43 of the latch 41 snaps over the arm 29, thus locking it in the first position. The 105 rocking of the lever 28 in a direction carrying the arm 30 away from the head 8 releases the valve 4, which because of the spring 8 and the air pressure within the pump at once seats to remain seated until 110 the pressure caused by the pump once more reaches or exceeds the predetermined maximum.

The action of the structure of the present invention is to maintain a constant pressure 120 at the delivery side of the pump within narrow limits with the relief-valve actuating means positively locked in both limits of its movement. Moreover, the action of the opening and closing means for the relief 125 valve is sudden and forceful, thereby preventing all chattering or uncertain action of the relief valve.

This application is a continuation of my application Serial No. 793,759, filed October 6, 1913.

What is claimed is:—

- 5 1. The combination with a pressure-producing pump provided with a relief valve, of a cylinder associated with the pump, a piston in the cylinder having a piston rod projecting therefrom, a rock lever connected 10 to the piston rod for actuation thereby, another lever having one end in position to engage the relief valve and open it, spring connections between each end of the first-named lever and the corresponding ends of 15 the second-named lever, and latches in the path of the first-named lever on opposite sides of its pivot and arranged in the path of the first-named lever for actuation thereby.
- 20 2. The combination with a pressure-producing pump having a relief valve, of a cylinder associated with the pump, a piston mounted in the cylinder, a spring in the cylinder tending to hold the piston at one 25 limit of its stroke, connections between the pressure side of the pump and the cylinder on the side of the piston remote from the spring, a piston rod carried by the piston and extending to the exterior of the cylinder, a rock lever connected on one side of 30 its pivot to the piston rod, another rock lever having one end in position to engage and open the relief valve, elastic connections between opposite ends of the first-named 35 lever and the corresponding opposite ends of the second-named lever, and latches in the path of the second-named lever on opposite sides of its pivot and also in the path of the first-named lever on opposite sides of its 40 pivot and operating to alternately latch and release the second-named lever at the limits of its rocking movements, said latches being in the path of the first-named lever for alternate actuation thereby to the unlatched 45 position.
3. The combination with a pressure-producing pump having a relief valve, of a cylinder associated with the pump, connections between the pressure side of the pump 50 and the cylinder, a diaphragm in the cylinder in position to be acted upon by fluid under pressure entering the cylinder through the connections with the pump, a piston in the cylinder on the side of the diaphragm 55 remote from the pressure connections, a spring in the cylinder tending to move the piston toward the diaphragm, a piston rod for the piston extending to the exterior of the cylinder, a rock lever connected to the piston rod for actuation thereby, latches in 60 the path of the opposite ends of the rock lever for alternate actuation thereby, another rock lever having its opposite ends positioned to move in alternation into en-
- gagement with the latches, and springs between the opposite ends of the first-named lever and the corresponding opposite ends of the second-named lever, said second-named lever having one end in position and having a range of movement to open the relief valve.
4. An automatic control for pressure-producing pumps provided with relief valves, comprising a pressure responsive member movable in one direction under pressure produced by the pump and having means imparting to it a normal constraint in the other direction, a rock member controlled by the pressure responsive means, another rock member adapted to open the relief valve, latches for the second rock member in position to latch it at opposite extremes of its movement, and spring connections between the first-named rock member and the second-named rock member on opposite sides of the axis of rocking of the rock members, the first-named rock member being in operative relation to the latches to actuate them and timed in movement with respect to the latches to put the second-named rock member under tensional strain to move in one direction or the other previous to unlatching it to such movement.
5. A device for the purpose described, comprising a cylinder, a piston therein, a piston rod connected to the piston and of a length to extend beyond the cylinder, a diaphragm in the cylinder in position to engage the piston, means for directing fluid under pressure against the diaphragm to move the piston, a spring in the cylinder imparting to the piston a constraint in opposition to pressure established within the cylinder, a rock lever mounted exterior to the cylinder and connected to the piston rod, another rock lever adjacent to the first-named rock lever, springs connecting the corresponding ends of the two levers together, a spring controlled latch lever in the path of one end of the first-named lever and having a latch nose in the path of the corresponding end of the second-named lever, and another spring controlled latch lever having one end in the path of the other end of the first-named lever, and a nose in the path of the corresponding end of the second-named lever, whereby rocking movements of the first-named lever to cause a corresponding rocking of the second-named lever through the spring connections and said rocking movements of the first-named lever to cause the unlatching of the second-named lever after the elastic tendency has been imparted thereto.
6. The combination with a pressure-producing pump provided with a relief valve, of means responsive to fluid pressure produced by the pump and including a member

movable by a predetermined fluid pressure, a rock lever having one arm in position to engage and open the relief valve, latches for the lever on opposite sides of its axis of 5 rocking, a rock member connected to and movable by the member responsive to a predetermined fluid pressure and on opposite sides of its axis of rocking in operative relation to respective ones of the latches, 10 and springs between the rock member and

the rock lever on opposite sides of the axis of rocking thereof.

In testimony that I claim the foregoing as my own, I have hereto affixed my signature in the presence of two witnesses.
